FLUID COOLING OF RECIPROCATING PISTONS

Ernest Edward Chatterton, London, England, assignor to
D. Napier & Son Limited, London, England, a company of Great Britain

Application November 8, 1954, Serial No. 467,613

Claims priority, application Great Britain
November 9, 1953

3 Claims. (Cl. 123—41.38)

This invention relates to pistons for internal combustion engines and of the kind comprising a crown portion and a skirt portion with a ring-carrying portion between them provided with one or more ring grooves, and more particularly to pistons for internal combustion engines designed to operate under high load or other conditions in which the rate of heat flow to the piston tends to be high.

It has already been proposed in the present applicant's British Patent No. 649,351 to provide a piston which is cooled in the neighbourhood of the ring grooves by the action of a cooling liquid which under the reciprocating action of the piston is shaken from one end to the other of an annular cooling chamber formed in the part of the piston around which the grooves lie and extending towards or into the skirt portion of the piston, and at the same time to provide a separate cooling circuit for the flow of cooling liquid through a crown-cooling chamber situated immediately beneath the piston crown.

The present invention is concerned with an improved arrangement of piston of the kind referred to tending to provide an increased transfer of heat to the cooling liquid and to prevent carbonisation of the cooling liquid and possible blockage of the cooling liquid passages due to carbonisation of the cooling liquid at high temperature points.

For convenience it will be assumed herein that the piston is vertical with its crown at its upper end, but it is to be understood that the invention is equally applicable to pistons having their axes horizontal or inclined as well as to pistons arranged with their crowns at their lower ends in cases where the speed of reciprocation of the piston during normal operation is such that the effect of momentum on the cool liquid outweighs gravitational effects.

According to the present invention a piston of the general kind referred to has an annular cooling oil chamber behind the ring groove or grooves extending towards or into the skirt portion and closed at its lower end, a crown cooling chamber extending across the under face of the crown from adjacent to its centre to adjacent to its circumference where it communicates with the adjacent upper end of the annular chamber, a series of loop passages leading from points intermediate in the length of the annular chamber to approximately the centre of the crown cooling chamber, means for admitting oil to the annular chamber and one or more oil outlets for the ejection of surplus oil from the annular chamber leading from the annular chamber at a point or points intermediate in its length, the arrangement being such that cooling oil thrown to the upper end of the annular chamber during the last half of each upstroke of the piston will tend to pass the lower ends of the loop passages and thus be forced by its momentum when it reaches the upper end of the annular chamber into and inwards through the crown cooling chamber into the upper ends of the loop passages whereby during the last half of the downstroke of the piston this oil will tend to be returned to

2

the annular chamber downwards through the loop passages.

The arrangement will preferably be such that the volumetric capacity of the part of the annular chamber which lies either above or below the oil outlet or outlets is smaller than the combined volumetric capacities of the crown cooling chamber and that part of the annular chamber which lies above the lower ends of the loop passages, so that the volume of oil retained in the annular chamber will be such that at the end of each upstroke of the piston the whole volume of oil in the annular chamber will tend to be thrown past the lower ends of the loop passages.

Moreover since the passage of oil from the upper end of the annular chamber into the crown cooling chamber at the moment when the oil reaches the upper end of the annular chamber may be somewhat delayed by the sudden change of direction, it may be preferable to make the volumetric capacity of the part of the annular chamber which lies either above or below the oil outlet or outlets not greater than the volumetric capacity of the part of the annular chamber which lies above the lower ends of the loop passages so that the whole volume of oil retained within the annular chamber can be accommodated in the part of this annular chamber above the lower ends of the loop passages.

In this connection it will be appreciated that during reciprocation of the piston each time the oil is thrown to that end of the annular chamber which has the lesser volumetric capacity measured from the transverse plane in which the outlet or outlets lie, surplus oil will tend to be ejected from the outlets, and that the quantity of oil maintained in the annular chamber during operation will tend to be approximately that which will just not cover these outlets when all the oil is thrown to such end of the chamber.

The details of construction may vary considerably but one construction of piston according to the invention is shown by way of example in the accompanying drawings, 40 in which

Figure 1 is a sectional side elevation of the piston and the upper end of its associated connecting rod in a plane at right angles to the axis of the gudgeon pin,

Figure 2 is a sectional elevation of the piston partly in each of two planes, that is on the line 2—2 of Figure 45 3, and

Figure 3 is a cross-section on the line 3—3 of Figure 2.

In the construction illustrated the piston comprises two main parts, namely an outer part comprising a crown A and a ring-carrying portion A¹ by which the crown is connected to the skirt portion A², and an inner part B which fits closely within the outer part after the general manner of a plug and includes the usual gudgeon pin bosses B¹ near its lower ends. The inner part B is retained within the outer part by means of a tapered circlip C engaging a groove in the skirt portion A² of the outer part as shown, and bearing through a thrust ring D on the lower end of the inner part B.

The inner circumferential surface of the outer part A¹, A², and the under surface of the crown A, and the outer circumferential surface and the upper surface of the inner part B are formed so that they co-operate to provide an annular oil cooling chamber comprising an upper part E lying behind the ring-carrying portion A¹ and a lower part E¹ which extends downwards into the skirt portion A² to a point just below the gudgeon pin F which is supported in the gudgeon pin bosses B¹, the part E of the annular cooling oil chamber communicating at its upper end with a crown cooling oil chamber comprising a series of radial passages G the inner ends

of which communicate with a pocket G^1 while their outer ends communicate with the upper end of the annular cooling oil chamber E , E^1 .

As shown in Figure 1, the connecting-rod H includes an oil delivery passage H^1 through which, in known manner, oil is fed from the crankshaft, this oil delivery passage, in addition to feeding oil to the gudgeon pin bearing H^2 , being arranged to deliver oil through an annular passage H^3 to a port H^4 which communicates with an oil receiving chamber J formed partly by a recess in the inner portion B of the piston and partly by a cylindrical surface on the gudgeon pin which makes a substantially oil-tight seal with corresponding surfaces at the edges of the recess J .

Formed in the inner part B of the piston are two oil inlet passages J^1 the inner ends of which communicate with the chamber J while their outer ends communicate with the annular cooling oil chamber E , E^1 as shown in Figure 2. Also formed in the inner part B of the piston, as shown in Figure 1, are two oil outlet ports J^2 by which oil can pass from the annular cooling oil chamber E , E^1 into the interior of the inner part B of the piston and thence out through the lower end of the piston.

Extending between the pocket G^1 and the annular cooling oil chamber E , E^1 are two loop passages each comprising an outwardly inclined section J^3 leading from the pocket G^1 and a substantially radial section J^4 leading from the lower end of the portion J^3 into the annular cooling oil chamber E , E^1 .

As shown the mean diameter of the lower end portion E^1 of the annular cooling oil chamber as well as its cross-sectional area are greater than the corresponding dimensions of the upper portion E , and the form of the parts is such that the change of direction of the oil flow at the junction of the upper and lower portions E , E^1 as the oil is thrown from the lower portion E^1 to the upper portion E towards the end of each upstroke of the piston will be completed before the oil reaches the lower ends J^4 of the loop passages J^3 , J^4 so that, when the oil is thrown upwards it will tend to be thrown past the ends of the passages J^4 into the upper end of the portion E of the annular chamber and thus into the crown cooling chamber G , G^1 , whence it will tend to flow to the appropriate level down the loop passages J^3 .

When during the following downstroke of the piston the oil then tends to be thrown to the lower end of the annular chamber E , E^1 , the part of the oil still in the upper portion E of this chamber will tend to be thrown directly downwards, since air from the lower end of the annular chamber can more readily reach this point than any point in the crown cooling chamber G , G^1 , while the oil in the upper ends of the loop passages J^3 , J^4 is thrown down through the loop passages into the annular chamber E , E^1 and tends to draw with it the oil in the crown cooling chamber G , G^1 .

It will be appreciated that during reciprocation of the piston oil will be delivered through the port H^4 , chamber J and passages J^1 into the annular chamber E , E^1 at an appropriate rate, and that oil will escape at a corresponding mean rate through the outlet ports J^2 .

At the same time during reciprocation of the piston there will be superimposed upon the delivery of oil to

and escape of oil from the annular chamber E , E^1 in the way mentioned, a circulation of oil round the circuit comprised by the upper part E of the annular chamber, the crown cooling chamber G , G^1 and the loop passages J^3 , J^4 . It will be appreciated that the quantity of oil maintained within the piston as a whole will tend to be controlled and maintained constant by reason of the position of the outlet ports J^2 , which ensures that only oil above a predetermined amount will be ejected from the piston during each reciprocation.

What I claim as my invention and desire to secure by Letters Patent is:

1. A piston of the kind referred to having an annular chamber behind the ring grooves extending towards the skirt portion and closed at its lower end, having an outer wall formed by the inner surface of the outer wall of the piston and an inner wall formed by an inner plug, a crown cooling chamber closely extending across the under face of the crown from adjacent to its center to adjacent to its circumference where the crown cooling chamber communicates with the adjacent upper end of the annular chamber, a series of loop passages formed in the said plug and leading in an upwardly inclined direction from points below the point where the crown cooling chamber communicates with the annular chamber to approximately the center of the crown cooling chamber, means for admitting oil to the annular chamber, and at least one oil outlet for the ejection of surplus oil from the piston formed in the inner wall of the annular chamber at a point intermediate in its length and below the lower ends of the loop passages and communicating with the exterior of the piston, the arrangement being such that the cooling oil thrown to the upper end of the annular chamber during the last half of each upstroke of the piston will tend to pass the lower ends of the loop passages and be forced by its momentum when it reaches the upper end of the annular chamber into and inwards through the crown cooling chamber into the upper ends of the loop passages, whereby during the last half of the downstroke of the piston this oil will tend to be returned to the annular chamber downwards through the loop passages.

2. A piston of the kind referred to as claimed in claim 1, in which the volumetric capacity of the part of the chamber lying below the oil outlets is substantially smaller than the combined volumetric capacities of the crown cooling chamber and that part of the annular chamber which lies above the lower ends of the loop passages.

3. A piston of the kind referred to as claimed in claim 1, in which the volumetric capacity of the part of the annular chamber which lies to the side of the oil outlet or outlets nearer one end of the annular chamber is not greater than the volumetric capacity of the part of the annular chamber which lies above the lower ends of the loop passage or passages.
